UNITED STATES PATENT OFFICE.

THOMAS GEORGE STILES, OF ARLINGTON, NEW JERSEY.

RAIL-BRACE.

1,230,533.

Specification of Letters Patent. Patented June 19, 1917.

Application filed April 21, 1915. Serial No. 22,753.

To all whom it may concern:

Be it known that I, THOMAS GEORGE STILES, a citizen of the United States, and a resident of Arlington, in the county of Hudson and State of New Jersey, have invented certain new and useful Improvements in Rail-Braces, of which the following is a specification.

This invention relates to a rail-brace, and particularly to an adjustable rail-brace for coaction with a rail-road rail, and the main object of the invention is to provide an improved rail-brace having means for fastening it securely, by suitable holding devices, in any position in which it may be set. These holding devices are located at different points or preferably run in two directions one substantially lengthwise of, and the other substantially transverse to, the rail to which the brace is applied. One of these holding devices is preferably a wedge locked in place in such a manner that it practically forms part of the rail-brace.

Heretofore it has been customary to employ holding devices for the rail-brace which would loosen up under the action of passing trains, especially if the rail-brace was adjustable. Here the main object is to prevent such loosening up of the parts by providing means which will hold the rail-brace positively under all conditions and preferably in two directions, that is, along two lines one of which is transverse to the other and one of which will resist displacement in one direction and the other of which will resist displacement in a direction transverse to the first.

The preferred means employed for holding the rail-brace proper in the manner before described embodies two pairs of serrated elements one pair running substantially lengthwise of the stock-rail and the other pair running substantially crosswise of said rail. Usually each pair of serrated holding elements is so combined with the other parts as to be capable of coöperating with a rail-brace adjustable to various positions. The construction ordinarily employed is one in which a comparatively long wedge or key having serrations thereon contacts with, and serves to locate positively, a rail-brace locatable in different positions crosswise of the stock-rail, according to the position of the wedge, and also interlocks with one or more parts for fastening down the rail-brace in such a manner that the

wedge and these parts and the rail-brace are all locked together by engaging serrations some of which run lengthwise of the stock-rail and others of which run crosswise of it, all of these parts being so combined as to be capable of being clamped down firmly upon a tie or tie-plate to hold the teeth of the engaging elements securely together.

Other features of my invention not hereinbefore referred to but which will be hereinafter described and claimed are illustrated in the accompanying drawings, in which,

Fig. 1 is a plan of a portion of a rail-road track showing the application of my invention to the stock-rails adjacent to the points of a switch.

Fig. 2 is a similar view, showing the rail-brace and holding device applied to a curve.

Fig. 3 is a similar view, illustrating the application of the invention to guard-rails and stock-rails at a point where guard-rails are applied, as for example at the intersection of two tracks.

Figs. 4, 5, and 6 are respectively a sectional elevation, a side elevation and a plan, each on an enlarged scale, of one of the rail-braces shown in Fig. 1.

Figs. 7 and 8 are respectively a plan and a sectional end elevation, each on an enlarged scale, of the type of rail-brace construction shown in Fig. 3 as applied to a stock-rail and an adjacent guard-rail.

Fig. 9 is a plan of a pair of adjacent wedging clamps shown in Figs. 7 and 8 for spacing the stock-rail and the guard-rail at the proper distance apart.

Similar characters designate like parts in all the figures of the drawings.

My improved rail-brace may be applied to track-rails at various points and for various specific purposes. Some of the main uses of it are illustrated generally in Figs. 1 to 3 inclusive, it being there shown as applied to stock-rails at switches and as applied to rails on curves and as applied to both stock and guard-rails at double-track crossings.

Referring first to Figs. 1, 4, 5, and 6, 2 designates the ordinary track-rail or stock-rail mounted on a suitable rail-support, in this case a tie-plate, 3, secured in the well known manner to a tie, 4. The stock-rail 2 is engaged substantially in the usual manner by a suitable rail-brace, such as B, which is of sufficient width to engage a considerable portion of the under side of the head of the

rail 2 and of corresponding width at all other points. This rail-brace may be secured to the tie-plate 3 and the tie 4 in any suitable manner, as for example by bolts, 5 such as 5, two of which are shown as extending through the tie and tie-plate and through elongated openings, such as 6—6, in the extended flat portion of the tail-piece of the rail-brace. This extension is indicated 10 at 7—7. The upper surfaces of the parts 7 of the rail-brace are shown as serrated in a direction crosswise of the rail-brace, that is lengthwise of the stock-rail 2, for engagement with corresponding serrated or toothed 15 washers, such as 8—8, through which the bolts 5 pass and the upper ends of which carry in this case tightening nuts, such as 9—9, with the usual small washers beneath them. The washers 8 are not round but are 20 elongated, the long portions extending outwardly in a direction transverse to the stock-rail and into position to coact with a suitable adjusting and holding device, preferably a wedge or key. The under side of each 25 washer 8 is in this case serrated not only in a direction crosswise of the rail-brace and lengthwise of the stock-rail but also in a direction lengthwise of the rail-brace and crosswise of said stock-rail. This is for the 30 purpose of coöperation with the wedge or key just referred to.

A wedge or key suitable for adjusting the rail-brace to different positions crosswise of the stock-rail and holding it in any position 35 to which it may be set is indicated at W. One edge of it is preferably at a right angle to the rail-brace and the tie on which said rail-brace is supported, while the opposite edge is diagonal to such tie, the wedge narrowing gradually from one end to the other and the wedge itself being longer than the rail-brace is wide in order to permit a considerable relative adjustment of the rail-brace with respect to the stock-rail. This 40 diagonal edge of the wedge is intended to abut against the extreme outer edge of the rail-brace proper and the opposite edge of the wedge is intended to engage a suitable fixed part, such as 10, along which it may 45 slide to shift the rail-brace proper either toward or from the stock-rail as the wedge is driven into the opening between the part 10 and the rail-brace proper or is drawn out of the same.

50 It will be noticed that the upper surface of the wedge W is serrated or toothed crosswise, that is, in a direction crosswise of the stock-rail and lengthwise of the rail-brace, these serrations, 11, being adapted to engage complementary serrations, such as 12, in the under sides of the outer ends of the extensions of the washers 8. In a similar 55 manner the other serrations, 13, of the washers 8 coact with complementary serrations, 14, at the upper sides of the extensions 7 of

the rail-brace, so that the teeth 11 and 12 lock the wedge along one line against movement in a horizontal plane, while the teeth 13 and 14 lock said rail-brace along a line at right angles to the line of the first set of teeth against movement in the same plane. It will be understood of course that when the two sets of teeth are in engagement the nuts 9 will be tightened up to hold all of the parts securely in place. Before being 70 brought into engagement, however, the desired adjustment will be effected by driving in the wedge W, this driving in of the wedge taking place before the two sets of teeth are brought together and, of course, before the 75 nuts 9 are tightened. Fig. 6 shows clearly how the two sets of teeth of the wedge, the washers 8 and the rail-brace proper are all interlocked after the parts have been properly adjusted and the nuts 9 screwed down 80 tightly.

In the construction shown in Fig. 2, a curved rail, 2', is illustrated, which is braced at both sides, my improved rail-brace B being shown as applied at one side of the rail and a fastening clip, b, at the other side of said rail. The construction and use of the rail-brace B shown in this view do not differ from the construction and use of the rail-brace previously described. The parts 90 B and b, however, are mounted on a support, such as the tie-plate 3', adapted to be fastened to the tie 4, this support having a stop at one end and the clip b clamped to the other end between which stop and clip all 95 the parts are wedged together.

In Figs. 3, 7, 8 and 9 I have illustrated the application of the invention to stock-rails having adjacent guard rails, as for example at the intersection of two tracks. In these 105 views the usual track-rail or stock-rail is indicated at 2, while g designates the guard-rail adjacent to it. In connection with these two rails I prefer to employ a pair of rail-braces of the type previously described, two 110 such rail-braces being shown at B. In this case, however, the two rail-braces are mounted on a tie-plate, 3'', of sufficient length to receive both the rails and a pair of rail-braces between two stops, 10', similar to that 115 shown at 10 in Fig. 1. The two rail-braces illustrated in these views do not differ substantially from those previously described, but they are fastened in place by short bolts, 120 such as 5', which extend through the tie-plate 3'' and through the extended outer ends of the rail-brace and also through the washers 8, these short bolts being secured in place to the parts and tightened up by means of suitable nuts 9, as before. The principal difference between the construction shown in these views and the devices illustrated in the other views is that the stock-rail and the guard-rail are positively spaced 125 at the desired distance apart by suitable 130

means, preferably by an adjustable combined clamp and brace, such as C, made up in this case of two main parts, both of wedge-like formation, one of which is designated by 15 and the other by 16. Part 15 has an upper flange, 17, which rests upon the upper adjacent edge of the part 16, and each of the two parts 15 and 16 is shown as having serrations or teeth which are brought into engagement when the parts 15 and 16 are adjusted at the proper position. One of these two wedging members of the clamp C has a depending element, 18, which is located in the corresponding opening, 19, in the support 3". When properly located at the desired position, with their teeth in engagement with each other, the parts of the clamp C, as will be obvious, space the stop-rail and the guard-rail positively at the desired distance apart. The two rail-braces B also positively engage these rails at the outside of the rails and thus coöperate to hold the rails rigidly both at the inner and the outer edges thereof, it being understood that the wedges of the two rail-braces B are driven home the necessary distance for locking all the parts up tightly, as will be clear by reference to Figs. 7 and 8.

In all of the various uses of my improved rail-brace it is desirable to make provision for some play crosswise of the rail-brace at the points where the bolts 5 or 5' pass through the parts. The elongated slots 6 previously referred to provide for not only play crosswise of the stock-rail but also, as before described, for a considerable range of adjustment of the rail-brace in this direction. In addition, however, to this movement it is desirable, as just stated, to provide for movement in the other direction, that is in a direction transverse to the rail-brace and lengthwise of the stock-rail. This is done by providing slots, 6', transverse to the slots 6, which permit slight movement, say $\frac{1}{16}$ to $\frac{1}{8}$ of an inch, crosswise of the rail-brace, for the purpose of enabling the washers 8 to shift slightly sidewise in case when the adjustment is complete, and before the nuts 9 are tightened down, the points or edges of the complementary serrations are opposite each other. This slight adjustment takes care of this condition by permitting sufficient sidewise movement to enable the teeth of one part to slip down into the tooth-spaces of the complementary part. After this the parts may be tightened up and locked together, as before described, by tightening the nuts 9.

While the construction shown is that which is preferred, it will, of course, be clear that I do not confine myself to the use of holding means for locks at two different points or along lines transverse to each other, as, with adjustable rail-braces, I may use the wedge and any suitable holding means by

which the rail-brace may be clamped and its length adjusted.

What I claim is:

1. The combination with a rail, a rail-support and a rail-brace extending transversely to said rail, of means for fastening said rail-brace, said means including holding devices having two sets of engaging horizontally disposed holding faces, one set running lengthwise and the other crosswise of said rail. 75

2. The combination with a rail, a rail-support and an adjustable rail-brace extending transversely to said rail, of means for fastening said rail-brace, said means including holding devices having two sets of engaging horizontally disposed holding faces, one set running lengthwise and the other crosswise of said rail. 80

3. The combination with a rail, a rail-support and an adjustable rail-brace extending transversely to said rail, of means for adjusting and fastening said rail-brace, said means including a wedge disposed substantially lengthwise of said rail and holding devices for the rail-brace and the wedge which holding devices have two sets of engaging horizontally disposed holding faces, one set running lengthwise and the other crosswise of said rail. 85 90

4. The combination with a rail, a rail-support and a rail-brace extending transversely to said rail, of means for fastening said rail-brace, said means including two pairs of holding devices, each pair having two engaging serrated members the serrations of one pair being disposed lengthwise and those of the other pair crosswise of said rail. 100

5. The combination with a rail, a rail-support and a rail-brace extending transversely to said rail, of means for fastening said rail-brace, said means including two pairs of holding devices lying substantially in a common plane, each pair having two engaging serrated members, the serrations of one pair being disposed lengthwise and those of the other pair crosswise of said rail. 105 110

6. The combination with a rail, a rail-support and a rail-brace extending transversely to said rail, of means for fastening said rail-brace, said means including a clamping device having serrated surfaces disposed transversely to each other and lying lengthwise and crosswise of the rail and a pair of coöperative serrated surfaces carried by the rail-brace. 115 120

7. The combination with a rail, a rail-support and a rail-brace extending transversely to said rail, of means for fastening said rail-brace, said means including a pair of clamping devices near opposite edges of the rail-brace each having serrated surfaces disposed transversely to each other and co- 125 130

- operative serrated surfaces carried by the rail-brace.
8. The combination with a rail, a rail-support and a rail-brace embodying a wedge for adjusting the length of said rail-brace, of means for fastening said rail-brace, said means including a clamping device having serrated horizontal surfaces disposed transversely to each other and a pair of cooperative serrated horizontal surfaces one carried by the rail-brace proper and the other by said wedge.
9. The combination with a rail, a rail-support and a rail-brace embodying a wedge for adjusting the length of said rail-brace, of means for fastening said rail-brace, said means including a pair of clamping devices near opposite edges of the rail-brace each having serrated surfaces disposed transversely to each other and cooperative serrated surfaces carried by the rail-brace proper and by said wedge.
10. The combination with a rail, a rail-support and a rail-brace embodying a wedge for adjusting the length of said rail-brace, the rail-brace proper being serrated horizontally lengthwise and the wedge crosswise of the rail, of clamping means for the rail-brace, said means embodying bolts and nuts for fastening the rail-brace to said rail-support and clamping washers under said nuts and serrated both lengthwise and crosswise of the rail to engage the serrations of the rail-brace proper and the wedge.
11. The combination with a rail, a rail-support and a rail-brace embodying a wedge disposed transversely thereto and of considerably greater length than the width of said rail-brace and operative for adjusting the rail-brace transversely to the rail, of means for fastening said rail-brace, said means including horizontally serrated holding devices disposed lengthwise and crosswise of said rail.
12. The combination with a rail, a rail-support and a rail-brace extending transversely to said rail, of means for fastening said rail-brace, said means including a clamping device having horizontal serrations running crosswise of the rail and cooperative serrations carried by said rail-brace, said clamping device and the rail-brace being constructed to have relative movement crosswise of said serrations.
13. The combination with a rail, a rail-support and a rail-brace extending transversely to said rail, of means for fastening said rail-brace, said means including a clamping device having horizontal serrated surfaces disposed transversely to each other and a pair of cooperative serrated surfaces carried by the rail-brace, said clamping device and the rail-brace being constructed to have relative movements crosswise of said respective pairs of serrations.
14. The combination with a rail, and with a rail-support adapted for attachment to a tie and having fixed stops near its ends, of a pair of rail-braces the inner ends of which engage said rail and the outer ends of which engage said stops, one of said rail-braces embodying fastening means having two sets of engaging horizontal serrations one set disposed lengthwise and the other disposed crosswise of said rail.
15. The combination with a rail, and with a rail-support adapted for attachment to a tie and having fixed stops near its ends, of a pair of rail-braces the inner ends of which engage said rail and the outer ends of which engage said stops, one of said rail-braces embodying an adjusting wedge and also embodying fastening means having two sets of engaging horizontal serrations one set disposed lengthwise and the other set crosswise of said rail.
16. The combination with a track-rail and with an adjacent guard rail, of a rail-support adapted for attachment to a tie and having fixed stops near its ends, means for spacing and holding said track-rail and guard-rail at a predetermined distance apart, and a pair of adjustable rail-braces the inner ends of which engage the outer sides of said rails respectively and the outer ends of which engage said stops respectively, each of said rail-braces embodying an adjusting wedge and also embodying fastening means having two sets of engaging serrations one set disposed lengthwise and the other set disposed crosswise of said rail.
17. The combination with a rail, a rail-support and an adjustable rail-brace extending transversely to said rail, of means for adjusting and fastening said rail-brace, said means including a wedge disposed lengthwise of said rail and adjustable by movement in the direction of its length and also including horizontal toothed holding devices carried respectively by the wedge and the rail-brace for clamping the wedge in any of its adjusted positions.
- Signed at New York, in the county of New York and State of New York this 31st day of March, A. D. 1915.
